HALF CYCLE DETECTOR FOR ELECTRONIC CONTROLS

Edward C. Hartwig, Tonawanda, N. Y., assignor to Westinghouse Electric Corporation, East Pittsburgh, Pa., a corporation of Pennsylvania

Application May 12, 1948, Serial No. 26,545

11 Claims. (Cl. 315—246)

1

My invention relates to electronic control systems and it has particular relation to protective devices for such system.

Electronic high-current switching devices or contactors have, for several years, been used in welding machines. In one such switching arrangement two ignitrons are provided to conduct alternating current of the two polarities. The ignitor current for each igniton is conducted from the power source through rectifiers and an ignitor switch to the cathode of the igniton so that when the switch is closed the ignitor receives current which causes the igniton to become conductive early in the part of the cycle during which the supply voltage is positive at its anode. Welding machines including this contactor are often operated by inexperienced persons who may fail to detect operational faults when such faults do not render the entire machine inoperative.

If one igniton of this contactor remains continuously non-conductive, the welder using this control will continue to operate but will make an imperfect weld. At the same time the welding transformer will receive unidirectional pulses. The flux in the welding transformer will build up and tend to saturate the transformer core, causing a reduction in the transformer impedance and a corresponding increase in current. The resulting overload current may severely damage the welder. It is impractical in most operations to set the main power line circuit breakers so that they will prevent such an overload since the circuit breakers might interrupt current in response to transient overloads or power source variations.

It is accordingly an object of my invention to provide a simple means whereby welding current shall be interrupted when either of the ignitrons of an ignition contactor is disabled.

Another object of my invention is to provide a simple and economical protective device to prevent overload in a current consumer supplied through an ignition contactor as a result of the failure of an igniton.

An ancillary object of my invention is to provide a firing network for an igniton contactor which shall operate to boost the firing current to a magnitude which will insure operation of the igniton.

Another ancillary object of my invention is to provide a protective network for an ignition contactor which shall also function as an effective firing network.

In accordance with my invention, firing cur-

2

rent for the ignitrons of an ignition contactor is transmitted through one of the windings of the transformer which may be called the secondary. The primary of the transformer is connected directly between the cathodes of the ignitrons; that is, in series with the source and load, through a fuse. When one of the ignitrons remains continuously non-conductive, this control transformer becomes saturated. The impedance of the control transformer is lowered and current through the primary is increased and the fuse blows. The flow of load current is then automatically stopped.

The novel features which I consider characteristic of my invention are set forth with particularity in the appended claims. The invention itself, however, both as to its organization and its method of operation, together with additional objects and advantages thereof, will be understood from the following description of a specific embodiment when read in connection with the accompanying drawing which is a diagrammatic view illustrating a preferred embodiment of my invention.

As illustrated in the drawing, current is supplied from a source of alternating current 3 through a pair of ignitrons 5 and 7 connected in anti-parallel to the primary 9 of the welding transformer 11. The secondary 13 of the transformer is connected between the electrodes 15 and 17 in engagement with material 19 to be welded. Each of the ignitrons includes an anode 21, a mercury pool cathode 23 and an ignitor 25 in contact with the cathode.

Transformer 32 is so connected to the ignitors of the ignitrons 5 and 7 that the terminal of the secondary 30 connected to the ignitor of igniton 5 is positive relative to the other terminal when the lower terminal of source 3 is positive relative to its other terminal.

Each igniton in effect has two ignition sources. One the main supply 3, the other the secondary 36. When the lower supply line of the source of alternating current 3 is positive with respect to the other supply line, the anode of the first igniton 5 is positive with respect to its cathode 23. One firing circuit for the first igniton 5 can be traced from the now positive lower terminal of the current source 3 through a line 27, the rectifier 29, the secondary winding 38 of the control transformer 32, a contactor 31, a rectifier 33, ignitor 25 and cathode 23 of the igniton 5 and the primary 9 of the welding transformer 11 to the other terminal of the source. The second

ignition circuit for the first thyratron 5 may be traced from the positive terminal of the secondary 30 of the control transformer 32 through contactor 31, rectifier 33, the ignitor 25, cathode 23 of thyratron 5, the fuse 41, the primary 39 of the control transformer 23, rectifier 29 to the negative terminal of the secondary 30. Under such circumstances an arc is ignited between the anode 21 and the cathode 23 of ignitron 5 and current flows through this ignitron.

When the upper terminal of the source 3 of alternating current is positive, the anode 21 of the ignitron 7 is positive with respect to its cathode 23. The first firing circuit of the second ignitron 7 may be traced from the upper terminal of the source 3 through the primary 9 of welding transformer 11, rectifier 35, contactor 31, the secondary winding 30 of the control transformer 32, rectifier 37, ignitor 25, the cathode 23 of second ignitron 7 to the other terminal of the source 3. The second ignition circuit of the second thyratron 7 may be traced from the now positive terminal of the secondary 30 of the control transformer 32 through rectifier 37, ignitor 25, cathode 23 of ignitron 7, the primary 39, the fuse 41, rectifier 35 and contactor 31 to the negative terminal of the secondary 30. Under such circumstances, an arc is ignited between the anode 21 and the cathode 23 of ignitron 7 and current flows through this ignitron.

The contactor 31 can be controlled by a timing system 43 such as is disclosed in my copending application, Serial No. 16,860, filed March 24, 1948, entitled "Timers" and assigned to Westinghouse Electric Corporation. The contactor 21 of my said application corresponds to contactor 31 here.

To initiate the welding operation, the contactor 31 is closed, allowing current to flow through the secondary 30 of the control transformer 32. Voltage induced in the secondary 30 of the control transformer 32 by the primary 39 adds to the voltage across the secondary 30 of the control transformer 32 and helps to force ignitor current through the ignitor circuit. The ignitron with which this circuit is to be used requires that the combined direct and induced current flow in its ignitor before the ignitron becomes conductive.

In the event that one of the ignitrons becomes disabled, the current flow through the control transformer 32 will be unbalanced. For example, assume that thyratron 5 becomes non-conductive. The voltage impressed on the primary 39 of the control transformer 32 during one-half period of the supply will be equal to the voltage drop across the second ignitron 7; therefore, the current flow will be small during this half period. During the other half period the full line voltage will be impressed across the primary 39 of the control transformer 32 and the current flow will be large. Such an unbalanced current flow will quickly lead to saturation of the control transformer 32. As the control transformer 32 becomes saturated, its inductance decreases, the current in the primary 39 in the control transformer 32 increases, and the fuse 41 is blown. The ignitor current is then sufficiently decreased to terminate the welding operation.

Although I have shown and described a specific embodiment of my invention, I am fully aware that many modifications thereof are possible. For example, the fuse may be replaced by a circuit breaker or by the actuating coil of a relay which, when activated, will open the circuit through the secondary of the control transformer.

The load supplied by the electronic contactor need not be a welding transformer. For example, the load may be a glass mass to be heated, an electric motor or any other of a large group of loads which require alternating current.

In accordance, also, with the broader aspects of my invention, the transformer 32 may be so connected that it blocks the source voltage during firing.

10 In view of these examples of practicable modifications of my invention I do not intend to restrict its scope except insofar as is necessitated by the prior art and by the spirit of the appended claims.

15 I claim as my invention:

1. For use in an apparatus having main valves for controlling the flow of current from a source through a load, and a control electrode in each main valve, the combination comprising a winding on a saturable core, a fuse, connections between said control electrodes and said winding and said fuse, connections between said winding and said valves so that when one of said valves becomes non-conductive, said winding receives current having a direct current component, and connections between said fuse and said control electrodes so that when said fuse is non-conductive said control electrodes do not provide a firing current and none of said main valves can become conductive.

20 2. For use in an apparatus having main valves for controlling the flow of current from a source through a load and a control electrode in each main valve, the combination comprising a winding on a saturable core, a current overload interrupter which interrupts current through said current overload interrupter when said current exceeds a predetermined magnitude, connections between said control electrodes to said winding and said current overload interrupter, connections between said winding and said valves so that when one of said valves becomes non-conductive, said winding receives current having a direct current component, and terminals for connecting said current overload interrupter to said control electrodes so that when said current overload interrupter is non-conductive said control electrodes do not provide a firing current and none of said main valves can become conductive.

25 3. For use in an apparatus for controlling the flow of current from a source through a load, the combination comprising main valves which conduct current from said source to said load, a control electrode in each of said main valves

30 to control the conductivity of said main valves, a first winding on a saturable core, a fuse, connections between said control electrodes and said first winding so that current flowing through said first winding provides current to said control electrode, a second winding on said saturable core adjacent to said first winding, said first and second windings being so wound and so connected to said power source that when current is flowing from said source, magnetic flux

35 produced by current from said source in said second coil opposes flux produced by current from said source in said first coil, said main valves being of such a nature that they will remain non-conductive unless their respective control electrodes are receiving current from both said first and said second windings, and connections between said fuse and said first winding so that, when said fuse is non-conductive, current in said first winding cannot be conducted to any one

40 of said control electrodes, said first winding be-

ing connected to said valves so that when any one of said valves remains non-conductive, said first winding receives current having a direct current component.

4. For use in an apparatus for controlling the flow of current from a source through a load, the combination comprising main valves which conduct current from said source to said load, a control electrode in each of said main valves to control the conductivity of said main valves, a first winding on a saturable core, a circuit breaker, terminals for connecting said control electrodes to said first windings so that current flowing through said first winding provides current to said control electrode, a second winding on said saturable core adjacent to said first winding, said first and second windings being so wound and so connected to said power source that when current is flowing from said source magnetic flux produced by current from said source in said second coil opposes flux produced by current from said source in said first coil, said main valves being of such a nature that they will remain non-conductive unless their respective control electrodes are receiving current from both said first and said second winding and connections between said circuit breaker and said first winding so that, when said circuit breaker is non-conductive, current in said first winding cannot be conducted to any one of said control electrodes, said first winding being connected to said valves so that when any one of said valves remains non-conductive, said first winding receives current having a greater magnitude when said current is of one polarity than when said current is of the other polarity.

5. For use in an apparatus for controlling the flow of current from a source through a load, the combination comprising main valves which conduct current from said source to said load, a control electrode in each of said main valves to control the conductivity of said main valves, a first winding on a saturable core, and a fuse, connections between said control electrodes and said first winding such that current flowing through said first winding provides current to said control electrode, a second winding on said saturable core adjacent to said first winding, a switch in circuit with said second winding so that the closing of said switch connects said second winding to said control electrodes and said power source, said first and second windings being so wound and so connected to said power source that when current is flowing from said source, magnetic flux produced by current from said source in said second coil opposes flux produced by current from said source in said first coil, said main valves being of such a nature that they will remain non-conductive unless their respective control electrodes are receiving current from both said first and said second winding and connections between said fuse and said first winding such that, when said fuse is non-conductive, current in said first winding cannot be conducted to any one of said control electrodes, said first winding being connected to said valves so that when any one of said valves remains non-conductive, said first winding receives current having a direct current component.

6. For use in an apparatus for controlling the flow of current from a source through a load, a first main valve to conduct current of one polarity to said load, a control electrode in said first main valve, a second main valve to conduct

current of the other polarity to said load, a first winding on a saturable core, a control electrode in said second main valve, said first winding being connected to the cathode of said first main valve and to the cathode of said second main valve, a second winding on said saturable core, rectifiers in circuit with said second winding, said rectifiers and said coils being connected so that current of one polarity flowing from said power source passes through said second winding to the control electrode of said second main valve, and current of the other polarity passes through said second winding to the control electrode of said first main valve, rectifiers connected to the cathode and the control electrode of both of said main valves so that current cannot flow from said cathode to said control electrode of the same main valve, said windings being so oriented that current flow from said source in one of said windings tends to induce increased voltage across the other winding.

7. For use in an apparatus for controlling the flow of current from a source through a load, a first main valve connected to conduct current of one polarity to said load, a control electrode in said first main valve, a second main valve connected to conduct current of the other polarity to said load, a first winding on a saturable core, a control electrode in said second main valve, said first winding being connected to a terminal of said first main valve and having its other terminal connected to a terminal of said second main valve, a second winding on said saturable core, rectifiers in circuit with said second winding, said rectifiers and said coils being connected so that current of one polarity flowing from said power source passes through said second winding to the control electrode of said second main valve, and current of the other polarity passes through said second winding to the control electrode of said first main valve, rectifiers connected to the cathode and the control electrode of both of said main valves so that current can flow from said cathode to said control electrode only through said second winding, said windings being so oriented that current flow from said source in one of said windings tends to induce increased voltage across the other winding.

8. For use in an apparatus for controlling the flow of current from a source through a load, a first main valve connected to conduct current of one polarity to said load, a control electrode in said first main valve, a second main valve connected to conduct current of the other polarity to said load, a first winding on a saturable core, a control electrode in said second main valve, said first winding being connected to the negative terminal of said first main valve and having its other terminal connected to the negative terminal of said second main valve, a second winding on said saturable core, rectifiers in circuit with said second winding, said rectifiers and said coils being connected so that current of one polarity flowing from said power source passes through said windings to the control electrode of said second main valve, and current of the other polarity passes through said windings to the control electrode of said first main valve, a switch in circuit with said second winding which controls current flow in said second winding, said windings being so oriented that current flow from said source in one of said windings tends to induce increased voltage across the other winding.

9. For use in an apparatus for controlling the flow of current from a source through a load, a

first main valve connected to conduct current of one polarity to said load, a control electrode in said first main valve, a second main valve connected to conduct current of the other polarity to said load, a first winding on a saturable core, a control electrode in said second main valve, said first winding being connected to the cathode of said first main valve and having its other terminal connected to the cathode of said second main valve, current overload interrupter which interrupts current through said current overload interrupter when said current exceeds a predetermined magnitude, a second winding on said saturable core, rectifiers in circuit with said second winding, said rectifiers and said coils being connected so that current of one polarity flowing from said source passes through said second winding to the control electrode of said second main valve, and current of the other polarity passes through said second winding to the control electrode of said first main valve.

10. In combination, a first valve having an anode, a cathode and a firing electrode, a second valve having an anode, a cathode and a firing electrode, a first connection between said anode of said first path and said cathode of said second, a second connection between said anode of said second path and said cathode of said first, and a saturable transformer having its primary connected between said first and second cathodes 25

and its secondary between said firing electrodes.

11. In combination, a first valve having an anode, a cathode and a firing electrode, a first asymmetric conductor connected to conduct from said cathode to said firing electrode, a second valve having an anode, a cathode and a firing electrode, a second asymmetric conductor connected to from said cathode of said second path to said firing electrode of said second path, a first connection between said anode of said first valve and said cathode of said second valve, a second connection between said anode of said second valve and said cathode of said first valve, a saturable transformer having its primary connected between said first and second cathodes and its secondary between said firing electrodes, and a circuit interrupter between said primary and said first and second cathodes.
